UNITED STATES PATENT OFFICE.

HARLAN S. WEBSTER, OF CANTON, OHIO.

COAL-DIGGER.

1,283,383.

Specification of Letters Patent. Patented Oct. 29, 1918.

Application filed January 12, 1918. Serial No. 211,595.

To all whom it may concern:

Be it known that I, HARLAN S. WEBSTER, a citizen of the United States, residing at Canton, in the county of Stark and State of Ohio, have invented new and useful Improvements in Coal-Diggers, of which the following is a specification.

This invention relates to new and useful improvements in machines for mining coal and the principal object of the invention is to provide means for cutting the coal from the vein and to convey the same to the rear of the machine.

Another object of the invention is to provide means for operating the cutting and conveying mechanisms and at the same time to move the machine to keep the cutting mechanism against the vein.

The invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:—

Figure 1 is a plan view of the complete machine.

Fig. 2 is a side elevation thereof.

Fig. 3 is a longitudinal section.

Fig. 4 is a plan view with parts omitted.

Fig. 5 is a rear view.

Figs. 6 and 7 are details of the chains and buckets.

In these views 1 indicates the bed plate of the machine which I preferably support on a caterpillar tractor mechanism indicated generally at 2. As this mechanism may be of any desired type I will not describe it in detail. This bed plate supports the motor 3, which may be of any desired type and power from this motor is transmitted to the caterpillar mechanism by means of the worm 4 on the shaft 6 of the motor engaging with the gear 5 carried by a shaft 6' to which is connected a suitable form of transmission device generally indicated at 7. This device is connected with the drive wheels 9 of the caterpillar arrangement by the gears 10, said wheels being located on shaft 8. By this means the machine may be driven forwardly at different speeds or it

may be reversed. A shaft 11 supported in the bearings 12 is driven from the motor by means of the gear 13 on the shaft 11 meshing with the worm 4. The shaft 11 is supplied with toothed wheels 14, one at each end thereof. The bed plate 1 at its forward end has an upwardly extending enlargement 1' to which is bolted a pair of supporting plates 15. As shown these plates extend forwardly beyond the bed plate and carry the cutter head 16 thereon. As shown this cutter head comprises a frame of slightly tapered formation and having its upper end wider than its lower end and said frame is supported in an inclined position on the plates with its lower end advanced. The upper and lower ends of the cutter head are provided with slots 17 communicating with grooved recesses 17', which together with the said slots form circular recesses to receive the toothed wheels 18 which are mounted on the shafts 19 carried at each end of the cutter head in suitable bearings therein. Each end of the cutter head is curved to conform to the circumference of the toothed wheels so as to entirely inclose said wheels, and each end of said head is removably secured in place on the head by the bolts 16' so that by removing these ends the toothed wheels with their shafts may be removed from the head. The outermost sets of wheels are connected with the toothed wheels 14 on the shaft 11 by means of the chains 20 which pass from the wheels 14 over the wheels at 90 the upper end of the cutter head then downwardly to the wheels at the lower end and then pass upwardly at an angle to the wheels 14, thus the toothed wheels of the cutter head are driven from the motor. Chains 21 are carried by the other wheels of the cutter head and these chains simply pass over the said wheels and along each side of the cutter head. All the chains have secured thereto the cutting means 22 which as shown in Figs. 6 and 7 consist of a solid link 23 forming part of the chain and having a bucket 25 formed thereon, said bucket having a cutting edge 24 thereon. As shown in Fig. 7 the bucket is considerably wider than the chain so that the front side of the cutter head is entirely covered by these buckets as said buckets have their edges in close proximity to the edges of the buckets on the same chain and to those on adjacent chains. The cutter head is provided with parallel vertical grooves 26 in each side to receive

these chains. On each side of the machine and extending from the front to the rear thereof are suitable conveyers 27 which receive the material from the hopper 28 located back of the cutter head, said conveyers being suitably driven from the motor. The shaft 11 is provided with suitable clutch means whereby the same may be thrown out of action so that the motor may be used to 10 operate the tractor mechanism without operating the cutting teeth.

When the machine has been moved into proper position by means of the caterpillar tractor the tractor may be stopped and the 15 motor switched on to the cutting mechanism so that the chains will be caused to travel over the toothed wheels. It will be seen that the buckets will move from the bottom of the head upwardly along the front side of the 20 head and over the toothed wheels at the top of the head; thus the buckets coming into contact with the coal in the vein will cut the same therefrom and the coal will drop into the buckets and will thus be carried upwardly over the cutter head and will be deposited in the hopper. This hopper will 25 pass the coal to the side conveyers which will carry it to the rear of the machine where it may be deposited in the cars or 30 the like. By means of the transmission mechanism the machine may be made to travel forward so as to keep the cutters against the vein of coal. It will be seen that 35 the cutters come into cutting position at the bottom of the device and at a point which is in the same horizontal plane as the

bottom of the tractor and owing to the fact that said cutters extend entirely across the front of the cutter head a clear track will be made upon which the tractor mechanism 40 may travel and all loose coal will be caught by the buckets and carried to the conveyers.

It is thought from the foregoing description that the advantages and novel features of my invention will be readily apparent. 45

I desire it to be understood that I may make slight changes in the construction and in the combination and arrangement of the several parts, provided that such changes fall within the scope of the appended claim. 50

What I claim is:—

A machine of the class described comprising a supporting frame, tractor means carried thereby, a motor on the frame, transmission means connecting the motor with the 55 tractor means, an inclined cutter head carried by the frame and having its lower end extending downwardly to a point in the same horizontal plane as the tractor means, said head having circular recesses in each 60 end thereof and grooves in its sides communicating with said recesses, toothed wheels located in said recesses, endless chains passing around said wheels and engaging said grooves, cutting teeth carried 65 by said chains and having pockets formed thereon, a driving shaft driven by the motor, and toothed wheels thereon over which some of the chains pass.

In testimony whereof I affix my signature. 70

HARLAN S. WEBSTER.
